SWITCH

John K. Asder, Los Angeles, Calif.

Application March 28, 1946, Serial No. 657,654

5 Claims. (Cl. 200—116)

1

This invention relates to switches and refers, more particularly, to a delayed action switch suitable for light and power circuits.

Patent No. 2,215,788 to J. W. Hamilton and J. K. Asder describes a switch of this nature comprising a thermostat of bi-metallic type, the heating element of which is arranged in a multiple circuit relationship with the load, so that the heating element can work concurrently with but independently of the load.

An object of the present invention is to improve the construction and the durability of a switch of this type.

Another object is the provision of a delayed action switch, which can be conveniently shut off in the daytime without delay.

A further object is to utilize well known mercury buttons for the construction of delayed action switches for the purpose of increasing the sturdiness and durability of the construction of such switches.

Other objects of the present invention will become apparent in the course of the following specification.

The above and other objects of the present invention may be realized through the provision of a delayed action switch having a mercury button connected to a manually operated knob and carrying a pin which may be swung along with the knob into the "on" position, the "off" position, or the "delayed action" position. In the "on" and "delayed action" positions the swingable pin cooperates with an arm causing it to maintain a given position, the electrical circuit for the heating coil of the bi-metallic element being completed only in the "delayed action" position of the switch.

The invention will appear more clearly from the following detailed description when taken in connection with the accompanying drawings showing by way of example a preferred embodiment of the inventive idea.

In the drawings:

Figure 1 shows diagrammatically and in side elevation a switch constructed in accordance with the principles of the present invention in the "on" position with a portion of the front of the casing removed.

Figure 2 is a left end elevational view of the switch shown in Figure 1.

Figure 3 is a right end elevational view of the switch shown in Figure 1.

Figure 4 is similar to Figure 1 and shows the switch in the "delayed action" position.

2

Figure 5 is similar to Figures 1 and 4 and shows the switch in its "off" position.

Figure 6 is a diagram showing the electrical connections of the switch in its "on" position.

Figure 7 is similar to Figure 6 and shows the electrical connections of the switch in delayed action position.

Figure 8 is similar to Figures 6 and 7 and shows the electrical connections of the switch in the "off" position.

The switch shown in the drawings may be conveniently affixed to a wall or carried upon a table or other supporting surface. This switch, in addition to its usual "on" and "off" positions, has a delayed action position into which it may be placed at will by the user. In this "delayed action" position lights will remain illuminated for a predetermined time period to enable the user to leave the premises while the lights are still on, whereupon the lights are automatically extinguished. Obviously, the switch is capable of other uses.

An important feature of the illustrated switch is that the user can shift it directly from the "on" position to the "off" position, for instance during daylight, when delayed action is not required.

The switch is carried by a casing 10, which may consist of Bakelite, porcelain or other suitable insulating material. For the sake of simplicity a portion of the front of the casing has been removed in Figures 1, 4, and 5.

The switch includes a manually operated knob 11, having a narrow finger-engaged portion 12 and a wider base portion 13. The portion 12 may be provided with an opening 14 for attaching a string or a chain.

The base portion 13 of the knob 11 is attached by rivets 15 and 16 to two fiber washers 17 and 18 (Fig. 3).

A mercury button switch 20 is firmly attached to the washers 17 and 18 and is rotatable therewith and along with shaft stubs 19.

Two brass fingers 21 and 22 are mounted in the casing 10 and engage the shaft stubs 19 of the mercury button switch on opposite sides. These fingers or contacts are used to establish an electrical connection through the mercury button switch 20 in the "on" and "delayed action" positions, the mercury button switch 20 being provided with a hole through a glass partition lowered below the level of the mercury in the "on" and "delayed action" positions which establishes an electrical path therethrough.

The contact 21 is fastened to the body 10 by

a screw 23, and is provided with a second screw 23A for attachment of the wire 47 (Fig. 6).

The other contact 22 is provided with similar screws 25 and 25A for respectively securing the contact to the body 10 and making the electrical connection to wire 48.

A coil spring 26 has one end which is attached to the casing 10 while its other end is attached to knob 11.

In the "on" position shown in Figure 1 the coil spring 26 is extended, so that its tendency is to swing the knob 11 to the right (looking in the direction of Figure 1), to the delayed action position shown in Figure 4 and thereafter to the off position shown in Figure 5.

The knob 11 is maintained in the "on" and "delayed" positions against the action of the spring 26 by means of a pin 27, which is disposed between fiber washers 17 and 18, coacting with the pivotally mounted arm 28 and spring 31 also co-acting therewith.

As shown in Figures 1 and 4, the pin 27 engages different parts of the upper periphery of the arm 28 in the "on" and "delayed" positions of the switch. The arm 28 is of irregular shape and is pivotally mounted intermediate its ends by a suitable pin 29, which passes through the Bakelite casing 10.

The pin 29 carries a spring 31 having an arm 32, which presses against the bottom periphery of the arm 28 and has a tendency to turn it counter-clockwise (looking in the direction of Figure 1). The arm 28 is prevented, however, from carrying out this rotation by means of the pin 27 or a pin 33, which is adapted to engage an inclined edge 34 of the arm 28 and which may be inserted into any one of a number of holes 35, located close to the edge 34 in such a manner as not to interfere with the operation of the arm 28.

As will be apparent more clearly hereinafter, the time of the delayed action may be conveniently varied by moving the pin 33 from one hole into another one.

In the "on" position shown in Figure 1, the pin 27 engages the inclined edge 34 of the arm 28. On the other hand, in the delayed position shown in Figure 4, the pin 27 is located within a recess 36 of the arm 28, the recess 36 being substantially shallow to permit the pin 27 to be readily moved in and out thereof and situated closer to the pin 29 than the edge 34.

In the "off" position shown in Figure 5 the pin 27 is entirely out of contact with the arm 28 which is still prevented from too great a counterclockwise movement from the spring 31 by the pin 33.

The washer 17 also carries on the outside surface portion thereof a conducting spring or a resilient contact 37, which is preferably made of bronze, turned outwardly and adapted to engage under tension the inside surface portion of the casing 10. The contact 37 is connected by a wire 39 to the terminal screw 25A. The wire 39 is sufficiently long, so that it will not interfere with the movements of the rotating portions of the switch.

A contact screw 33 extends through the Bakelite casing 10 and is adapted to form an electrical contact with the spring 31 in the delayed action position shown in Figure 4.

The contact screw 33 is connected to one side of the heating coil or element 40 (wire 39A, Fig. 6), which comprises a part of the delayed action circuit. The remaining end of the element 40 is

connected to a metallic plate 61 (Fig. 3) provided with a screw 62 for securing the wire 39 and the said plate to the body 10. A screw 23B, threaded into the plate 61, is used to connect the delay circuit to the power source. The heating element 40 is preferably wound over a layer of asbestos which covers the bimetallic element 42.

One end of the bimetallic element 42 is attached by screws 43 to the casing 10, the other end having a sharp bend 44 positioned close to the end 45 of the pivotally mounted arm 28. When the bimetallic element 42 is bent due to heating, it will engage the end 45 of the arm 28 and swing the arm clockwise (looking in the direction of Figure 4), thereby withdrawing the pin 27 from the substantially shallow recess 36 and enabling the spring 26 to swing the knob 11 and the parts connected therewith to the off position shown in Figure 5.

The load circuit may consist of a lamp 46 as shown in Figures 6, 7, and 8 connected to a suitable source of electric current such as the battery 46A, wires 47 and 48 being connected to the previously described terminals 23A and 25A on the casing 10.

In the "off" position, shown in Figure 5, and indicated diagrammatically in Figure 3, the load circuit contact and the heating circuit are both open since the mercury button switch 28 is so mounted that in the "off" position the hole through the glass partition of the switch is above the level of the contained mercury thereby interrupting the electrical path therethrough. The heating circuit is also open for the same reason and the additional reason that the contact 37 and the co-acting contact screw 28 are disengaged in the "off" position.

Light is switched on by the user by swinging the knob 11 from the "off" position, shown in Figures 5 and 8, to the "on" position shown in Figure 1 and indicated diagrammatically in Figure 6. In the "on" position, the hole through the glass partition of the mercury button switch 28 is lowered below the level of the contained mercury thereby providing an electrical path therethrough, thence through the brass fingers 21 and 22 to the terminals 23A and 25A. The electrical circuit, as shown in Figure 6, is as follows: From the battery 46A, the current passes through the conductor 47 to the terminal 23A, thence through the brass finger 21, the mercury button switch 28, as previously shown, out through the brass finger 22 to the terminal 25A, thence through the conductor 48 to one side of the light load 46, and thence out the opposite side of the light load 46 to the opposite terminal of the battery 46A. During the "on" position, the pin 27 is in contact with the edge 34 of the arm 28 and remains in that position, until manually moved, by the action of the spring 31 on the pivotally mounted arm 28. To reverse the movement, that is to bring the switch 28 back to the "off" position shown in Figure 5, the knob 11 is merely pushed clockwise which forces the pivotally mounted arm 28 downwardly by the pin 27 against the action of the spring 31 until the pin 27 is shown in the position of Figure 5.

On the other hand, the user may decide to move the switch to the delayed action position. As shown in Figures 4 and 7, the knob 11 is then located in an intermediate position, and is held in that position by the engagement of the pin 27 with the substantially shallow recessed portion 36 of the arm 28.

In this delayed action position, the contact 31

is in electrical engagement with the contact screw 38, and the hole through the glass partition of the mercury button switch 20 is lowered below the level of the contained mercury thereby providing an electrical path therethrough, thence through the brass fingers 21 and 22 to the terminals 23a and 25a. The electrical circuits, as shown in Figure 7, are as follows: For the light load 46, the current passes from the battery 46a through the conductor 47 to the terminal 23a, thence through the brass finger 21, the mercury button switch 20, as previously shown, out through the brass finger 22 to the terminal 25a, thence through the conductor 48 to one side of the light load 46, and thence out the opposite side of the light load 46 to the opposite terminal of the battery 46a. For the heating coil or element 40, the current passes from the battery 46a through the conductor 47 to the terminal 23a, thence through the brass finger 21, the mercury button switch 20, as previously shown, out through the brass finger 22 to the conductor 39, thence to the contact 37 and through the co-acting contact screw 38 to the conductor 39a, thence around the bimetallic strip 42 to the conductor 30 and terminal 23b to complete the circuit to the battery 46a.

The switch will remain in this position until the bimetallic spring 42 is bent as a result of the heating; then the end 44 of the bimetallic element will engage the outer end 45 of the arm 28 and will swing the arm clockwise (looking in the direction of Figure 4), thereby withdrawing the shallow recessed portion 36 of the arm 28 from engagement with the pin 27. As soon as the arm 28 is withdrawn the spring 26 will pull the knob 11 to the "off" position shown in the Figure 5. It is apparent that the position of the end 45 of the arm 28 in relation to the end 44 of the bimetal 42 may be conveniently varied by placing the pin 33 in different holes 35 so positioned as not to interfere with the operation of the arm 28 but providing a convenient means for varying the time interval of the delayed action.

It is apparent that the specific illustration shown above has been given by way of illustration and not by way of limitation, and that the structure above described is subject to wide variation and modification without departing from the scope or intent of the invention. For example, the mercury button switch may be conveniently replaced by a mercury tube. All of such and other variations and modifications are to be included within the scope of the present invention.

What is claimed is:

1. In an electrical switch, a pivoted operating member swingable to "on," "delayed action" and "off" positions, contacts engaging said member, means carried by said operating member and establishing an electrical connection between said contacts in the "on" and "delayed action" positions of said operating member, said contacts being electrically disconnected in the "off" position of said operating member, a pivoted arm adjacent said operating member, a locking member carried by said operating member and movable therewith, said arm having abutments located in the path of movement of said locking member to engage said locking member in the "on" and "delayed action" positions of said operating member and to hold said operating member in such positions, and being devoid of contact with said locking member in the "off" position of said operating member, a thermostatic element mov-

able when heated from an inoperative position to a position wherein it swings said arm about its pivot and disconnects it from engagement with said locking member, means connected with said operating member and moving it to its "off" position when said locking member is not engaged by said arm, and heating means associated with said thermostatic element and adapted to heat the same.

10 2. In an electrical switch, a pivoted operating member swingable to "on," "delayed action" and "off" positions, contacts engaging said member, means carried by said operating member and establishing an electrical connection between said contacts in the "on" and "delayed action" positions of said operating member, said contacts being electrically disconnected in the "off" position of said operating member, a pivoted arm adjacent said operating member, a locking member carried by said operating member and movable therewith, said arm having abutments located in the path of movement of said locking member to engage said locking member in the "on" and "delayed action" positions of said operating member and to hold said operating member in such positions and being devoid of contact with said locking member in the "off" position of said operating member, a spring engaging said arm, a thermostatic element movable when heated from an inoperative position to a position wherein it swings said arm about its pivot against the action of said spring and disconnects it from engagement with said locking member, a spring connected with said operating member and moving it to its "off" position when said locking member is not engaged by said arm, heating means associated with said thermostatic element, a contact connected with said heating means, another contact carried by said operating member and engaging the last-mentioned contact in the "delayed action" position of the operating member, and conducting means connecting the first-mentioned contacts in parallel with said other contacts, whereby said thermostatic element is heated by said heating means when said operating member is in its "delayed action" position.

3. In an electrical switch, a pivoted operating member swingable to "on," "delayed action" and "off" positions, contacts engaging said member, a mercury switch carried by said operating member and movable therewith to establish an electrical connection between said contacts in the "on" and "delayed action" positions of said operating member and interrupting said connection in the "off" position of said operating member, a pivoted arm adjacent said operating member, a locking member carried by said operating member and movable therewith, said arm having abutments located in the path of movement of said locking member to engage said locking member in the "on" and "delayed action" positions of said operating member and to hold said operating member in such positions and being devoid of contact with said locking member in the "off" position of said operating member, a thermostatic element movable when heated from an inoperative position to a position wherein it swings said arm about its pivot and disconnects it from engagement with said locking member, means connected with said operating member and moving it to its "off" position when said locking member is not engaged by said arm, and heating means associated with said thermostatic element and adapted to heat the same.

4. In an electrical switch, a pivoted operating member swingable to "on," "delayed action" and "off" positions, contacts engaging said member, means carried by said operating member and establishing an electrical connection between said contacts in the "on" and "delayed action" positions of said operating member, said contacts being electrically disconnected in the "off" position of said operating member, a pivoted arm adjacent said operating member, a locking member carried by said operating member and movable therewith, said arm having abutments located in the path of movement of said locking member to engage said locking member in the "on" and "delayed action" positions of said operating member and to hold said operating member in such positions and being devoid of contact with said locking member in the "off" position of said operating member, a bi-metallic element movable when heated from an inoperative position to a position wherein it swings said arm about its pivot and disconnects it from engagement with said locking member, means connected with said operating member and moving it to its "off" position when said locking member is not engaged by said arm, heating means associated with said bimetallic element, a contact connected with said heating means, another contact carried by said operating member and engaging the last-mentioned contact in the "delayed action" position of the operating member, and conducting means connecting the first-mentioned contacts in parallel with the last-mentioned contacts and said heating means whereby said bi-metallic element is heated by said heating means when said operating member is in its "delayed action" position.

5. In an electrical switch, a non-metallic casing having a recess formed therein, an operating member pivotally mounted in said recess and

swingable to "on," "delayed action" and "off" positions, contacts engaging said member, a mercury switch carried by said operating member and movable therewith to establish an electrical connection between said contacts in the "on" and "delayed action" positions of said operating member and interrupting said connection in the "off" position of said operating member, an arm pivoted in said casing below said operating member, a locking member carried by said operating member and movable therewith, said arm having abutments located in the path of movement of said locking member to engage said locking member in the "on" and "delayed action" positions of said operating member and to hold said operating member in said positions and being devoid of contact with said locking member in the "off" position of said operating member, a spring engaging said arm, a thermostatic element movable when heated from an inoperative position to a position wherein it swings said arm about its pivot against the action of said spring and disconnects it from engagement with said locking member, a spring connected with said operating member and moving it to its "off" position when said locking member is not engaged by said arm, and heating means associated with said thermostatic element and adapted to heat the same.
